UNITED STATES PATENT OFFICE.

GIBBARD R. HUGHES AND THOMAS CARWARDINE, OF HAMPSTEAD, COUNTY OF MIDDLESEX, ASSIGNEES TO THE GRAPHO PEN MANUFACTURING COMPANY, (LIMITED,) OF LONDON, ENGLAND.

APPARATUS FOR SUPPLY OF INK TO PENS.

SPECIFICATION forming part of Letters Patent No. 281,968, dated July 24, 1883.

Application filed January 26, 1883. (No model.) Patented in England August 31, 1882, No. 4,152; in Germany September 6, 1882, No. 22,511; in Belgium September 7, 1882, No. 58,967, and in France September 8, 1882, No. 151,018.

To all whom it may concern:

Be it known that we, GIBBARD RICHARD HUGHES and THOMAS CARWARDINE, subjects of the Queen of Great Britain and Ireland, residing at Hampstead, in the county of Middlesex, England, have jointly invented certain new and useful Improvements in Means or Apparatus for the Supply of Ink or Writing-Fluid to Pens, (for which we 5 have obtained a patent in Great Britain, No. 4,152, dated August 31, 1882; in France, No. 151,018, dated September 8, 1882; in Belgium, No. 58,967, dated September 7, 1882, and in Germany, No. 22,511, dated September 10 15 6, 1882;) and we do hereby declare that the following is a full, clear, and exact description of the invention, which will enable others skilled in the art to which it appertains to make and use the same, reference being had 20 to the accompanying drawings, and to letters or figures of reference marked thereon, which 25 form a part of this specification.

The invention relates to improvements in ink-supplying means or apparatus for writing-pens of the reservoir or fountain kind; and the objects of our improvements are, first, to 30 protect the pen from corrosion by keeping the ink out of actual contact therewith, except at or near the points or nib; and, second, to prevent flow of ink at the nib except when the pen is in actual use in writing; third, to prevent escape of ink from the holder of the pen during carriage in the pocket, or otherwise; and, fourth, the better control of the ink in 35 the reservoir and in its flow to the pen. We prefer to attain these objects by the mechanism illustrated in the accompanying drawings, in which—

Figure 1 shows a vertical section of the entire pen and holder. Fig. 2 shows a sectional view. Fig. 3 a side view. Fig. 4 an upper side, and Fig. 5 an under side view, respectively, of the pen and its ink-conductor attachment separated from the holder and reservoir parts. Fig. 6 shows the bag or conductor hereinafter more particularly referred to separately.

Similar letters refer to similar parts throughout the several views.

a is the pen proper or nib, having its barrel 50 portion *a'* enveloped by one portion, *b'*, of the india-rubber bag *b*, such portion being for this purpose turned inside out over it. The remainder of the bag does not envelop or jacket the pen; but its other end, *b*², is twice punctured or passed through by the points of the nib *a'*, such points entering from the outside of the bag and emerging from the side opposite that at which it enters, thus puncturing the bag substantially transversely. This bag-enveloped pen *a* is then socketed or held in the conically-shaped opening *c'* of the part *e* of the main holder, and this part *e* is screwed to the part *d'* of the reservoir *d*, while the part *d'* thereof again is screwed to the part of the 60 holder *e*, which part *e* is screwed at *c'* to the part *f'* of a connecting-plug, *f*, upon the part *f*² of which plug a perforated end piece, *g*, is slid, the reservoir *d* having been filled with ink by unscrewing the parts *d* and *c'*. 7⁶

The operation of the apparatus in working is as follows: Pressure of the nibs on the surface to be inscribed causes their separation, and this opening of these nibs also opens the elastic end of the bag *b* through which they 75 pass, and so permits ink to flow out in a thin stream, while their removal from the written surface permits the nibs and the enveloping end of the bag to reclose, stopping the flow of ink. The perfect action of these parts in preventing the flow of ink except in actual use is secured by dipping or coating the pen and bag with india-rubber or other suitable elastic solution after they have been attached together, completing the sealing of the closed nibs with 80 the perforated small end of the ink bag. Ink to the ink-bag *b* flows therein by its open end *b*² from the ink-reservoir *d* down the channel or chamber *c'*. Chambers *c'*, *e'*, and *g'* are formed by the spaces left between the adjoining parts *e* and *d*, *d* and *e*. *d*, *e*, and *f*, *f* and *g* and the chambers *c'*, *e'*, and *g'* are connected for the passage of air by channels *d'* *c'* *f'*, which air enters by the perforations *g'*, while the chamber *e'* further serves as a catch-chamber or interceptor to intercept ink that may escape through these air-passages in what would be an undesirable and inconvenient direction 85

with danger of eventual escape into the pocket or hand. For still greater security in some cases, we slide or otherwise secure over the outer end, *g*, an unperforated cap or cover, (not necessary to be shown,) and when the pen is out of use such cap or cover and the cap or cover *g* may be slid on over the pen end of the holder to protect those parts.

We are aware that it has been before proposed to inclose the whole pen in a bag or case of sheet india-rubber, which case was opened by the separation of the nibs by pressure on the surface to be written. The pen, if of corrodible metal, soon suffers from corrosion by the action of the ink by which it is surrounded constantly; but such plan is inimical to one of the primary objects of our invention, which is to keep the ink out of contact with the nibs of the pen as much as possible, and to localize the corrosion to the very small part of the nibs down which the ink actually flows in working and the parts passing through the bag end.

What we claim as our invention is—

1. In a reservoir writing-pen, the ink-conveying bag *b*, in combination with a pen, the nibs of which project through both sides of the bag, substantially as shown and described.
2. In a reservoir-pen, the combination of the ink-conveying bag with a pen which punctures and projects through both sides of the

same, the pen-points being covered with a luting or coating of india-rubber or other suitable elastic solution, to complete the sealing of the closed nibs, all substantially as set forth.

3. In a reservoir writing instrument or pen, 35 the combination, with a pen or nib, of an elastic ink-supplying bag, *b*, applied thereto, as shown and described, and through the opposite sides of which the nibs of the pen project, and a reservoir ink-holder arranged to supply 40 ink to such bag, all substantially as shown and described.

4. In a writing instrument or pen, the combination of a pen or nib having an ink-supplying bag through which the nibs of the pen 45 project, and luted or coated with an elastic solution, as set forth, with a socket, *c*, reservoir *d*, cylindrical piece *e*, plug *f*, and cap *g*, air-passages, and an ink catchment chamber being provided in the respective parts, all 50 substantially as shown and described.

In witness whereof we, the said GIBBARD RICHARD HUGHES and THOMAS CARWARDINE, affix our signatures in the presence of two witnesses.

GIBBARD R. HUGHES.
THOMAS CARWARDINE.
